(57) **CLAIM**

The ornamental design for a construction set element, as shown and described.

DESCRIPTION

FIG. 1 is a top perspective view of a construction set element showing the new design;

FIG. 2 is a top plan view of the construction set element of FIG. 1;

FIG. 3 is a bottom plan view of the construction set element of FIG. 1;

FIG. 4 is a front elevational view of the construction set element of FIG. 1;

FIG. 5 is a rear elevational view of the construction set element of FIG. 1, from the position of line 5-5 in FIG. 2; FIG. 6 is a right side elevational view of the construction set element of FIG. 1, from the position of line 6-6 in FIG. 2; and,

FIG. 7 is a left side elevational view of the construction set element of FIG. 1, from the position of line 7-7 in FIG. 2. The evenly spaced broken lines and unshaded areas form no part of the claimed design. The long and short broken lines in FIGS. 1, 2, and 4-7 define the bounds of the claimed design and form no part thereof. The various directional adjectives used in this specification, such as “front,” “rear,” “right,” “left,” “top,” and “bottom,” refer to the construction set element as illustrated.

1 Claim, 7 Drawing Sheets
